his ATTORNEY:

UNITED STATES PATENT OFFICE.

CARL RUDQVIST, OF MUNICH, GERMANY.

TWO-STROKE-CYCLE ENGINE.

1,392,359.

Specification of Letters Patent.

Patented Oct. 4, 1921.

Application filed December 12, 1916. Serial No. 136,582.

To all whom it may concern:

Be it known that I, CARL RUDQVIST, a subject of the King of Sweden, and resident of Munich, Germany, have invented 5 certain new and useful Improvements in Two-Stroke-Cycle Engines, whereof the following is a specification.

In certain types of existing two cycle engines the same mixture is used for scavenging 10 and charging purposes, as these two actions are effected simultaneously. This is however, a defect which greatly contributed to this type of engine being superseded by the four cycle engine.

One object of the present invention is to improve in two cycle engines the scavenging 15 process in such manner that it occurs in two phases, while the charging operation is entirely separate and distinct from the scavenging process.

To this end I employ an engine comprising two parallel cylinders, the pistons of which are connected to a common crank, the crank-shaft being situated in, or approximately in, the middle plane of the two cylinders which have a common combustion chamber and common admission and exhaust ports, controlled by said pistons. On the descent of the piston the air to be used 20 for scavenging is compressed in a known manner in the engine casing and on the up stroke of the piston the air is sucked from the outside through a valve, slide or the like, automatically operated or controlled.

In the scavenging device according to the present invention the scavenging air is first fed into one cylinder through scavenging ports located in the wall of this cylinder, controlled by the piston, and after the opening 25 of the exhaust port in the other cylinder a portion of the scavenging air flows into such other cylinder through ports in the wall of the same, in such manner that this part of the scavenging air not only drives off the residue of the exhaust gases through the exhaust port in a quicker and more reliable manner, but also owing to the speed at which it rushes through the exhaust port exerts a suction action upon 30 the scavenging air, already admitted into the first cylinder and which has entered the second cylinder through the common combustion chamber, so that further scavenging of the second cylinder takes 35 place nearly free from eddy currents.

After the closure of the exhaust port at the end of the scavenging operation the admission port for the charging mixture is uncovered by the first cylinder piston and the charge is compressed by a special pump, 60 driven from the engine shaft, and fed to the admission port under the control of a rotary valve, driven from the engine shaft.

This rotary valve, which constitutes a further improvement of the two stroke 65 cycle engine, forms a kind of storage chamber for the charging air or the charging mixture and may communicate, by appropriate ports, with the cylinder and with the charging pump. Within the casing of the 70 rotary valve is a small chamber in the wall of which are suitably positioned ports by means of which such chamber may either be placed in communication with a carburetor or with fresh air or with the charging 75 pump.

By this special construction of the rotary valve, extending across the whole width of the engine and its arrangement at a right angle to the charging pump the whole structure and operation of the two cycle engine 80 is essentially simplified and improved.

Finally a further improvement of the two cycle engine consists in providing one piston rod with a journal extending over the 85 whole crank pin, while the other piston rod is connected to the first one just above the journal or, if the two are made of one piece, is attached to same.

For the purpose of its being journaled on 90 the crank pin it is convenient, the direction of rotation of the crank shaft being that of the hands of a watch, to employ the piston rod of the leading piston and to connect the piston rod of the lagging piston to the other 95 crank bearing.

By such an arrangement the main pressures, imposing a bending and buckling stress on the crank pin and arising from the leading piston, are on the one hand transmitted directly through its whole length and, on the other hand, a certain elasticity is given the whole gear and thereby, thus even with improper adjustment of the pistons, eccentric grinding of the cylinders is 100 prevented and the action of the inertia forces lessened.

In the drawing a two cycle engine provided with the new improvements is shown in Figures 1 and 2 in two longitudinal sec- 110

tions perpendicular to each other and in Fig. 3 in a cross section on the line A—B. Fig. 4 is a section on the line C—D of Fig. 3.

The two cylinders *a* and *b* are provided with the pistons *c*, *d*, whereof the former leads the latter during the explosion and compression period, and the piston rods *e* and *f*. The latter are either made of a single piece and connected to the crank shaft 10 *g* or the rod *e* of the leading piston *c*, is as shown, set on the crank pin with a bearing *e*¹ extending over its full length and the piston rod *f* is connected at *f*¹ to the piston rod *e*.

15 The engine casing *h* serves as a scavenging air chamber and is automatically or in a controlled manner supplied, through a valve or slide, with the outer air.

The admission port for the mixture of 20 fuel and air, common to the two cylinders *a*, *b* is denoted by *i*, the common combustion chamber by *k* and the common exhaust port by *l*.

The scavenging air leaves, on the one 25 hand, the crank casing *h* by the ports *m* located in the wall of the cylinder *b* under control by the piston *d*, and enters, on the other hand, by the openings *m*¹, provided in the wall of the cylinder *a* behind the partition wall *h*¹ of the casing *h*. Consequently 30 the cylinder *b* is first of all scavenged by the air issuing through the ports *m*, which air drives the exhaust gases through the ports *n* into the conduit *l*. The exhaust of the 35 remaining portion of the burnt gases and the completion of the process of scavenging the cylinder *a* is effected by the scavenging air streaming out of the ports *m*¹ which produces a sucking action on the contents of 40 the cylinder *b*, thereby completely cleaning the same from the burnt gases.

After the completion of the scavenging and the exhaust process the charge is admitted which is produced by the charging 45 pump *o*, the piston *p* of which is driven by the eccentric *r*, directly mounted on the engine shaft at the end opposite to the fly-wheel *q*, and the piston rod *s*.

The charging pump *o* communicates by a 50 pipe *t* with the charging valve *u*, *v*, extending across the whole width of the engine, in the casing *w* and driven from the fly-wheel-side of the engine by a chain-gearing *x* or the like.

55 The chamber *u* of the valve serves as a collector for the mixture and communicates, by the port *u*¹, with the admission-opening *i*, and a second port *u*² coöperates with the piping *t*.

60 The chamber *u* has formed therein, opposite to the connecting end of the piping *t* and the port *u*² respectively, the chamber *v*, provided with a port *v*¹, arranged at its outer periphery and diametrically opposite 65 to the port *u*² with regard to the axis of

the valve. The second port *v*² of the chamber *v* is located at the outer front-wall of the chamber and communicates with the connecting socket *y* for the carburetor or the pipe for the supply of fresh air.

This arrangement renders it possible to feed in due time into the cylinders an easily controllable quantity of mixture, thereby greatly increasing the useful work of the engine, this being also due to the nature of 75 the admission.

What I claim as my invention and desire to secure by Letters Patent is:—

1. In a two cycle internal combustion engine, the combination with a casing having 80 a compressed air chamber therein, of a pair of cylinders within said casing the wall of each cylinder having openings through which compressed air from said chamber may flow, a combustion chamber common to 85 both cylinders at one end thereof, a fuel admission passage communicating with one of said cylinders, an exhaust passage communicating with the other of said cylinders, a piston operable in each cylinder, and means 90 for operating said pistons whereby the openings in the cylinder communicating with the admission passage are first uncovered to the flow of compressed air from the compressed air chamber to scavenge 95 such chamber and thereafter the second piston is moved to uncover the openings therein and the exhaust passage whereby compressed air will flow through said last named openings to cause a suction action 100 in both cylinders and complete the scavenging operation.

2. In a two cycle internal combustion engine, the combination with a casing having 105 a compressed air chamber therein, of a pair of cylinders within said casing the wall of each cylinder having openings through which compressed air from said chamber may flow, a combustion chamber common to both cylinders at one end thereof, a fuel admission passage communicating with one of said cylinders, an exhaust passage communicating with the other of said cylinders, a piston operable in each cylinder, certain 110 of the openings in the cylinder adjacent the exhaust passage being adapted to communicate with the latter, and means for operating said pistons to first uncover the openings in the cylinder adjacent the fuel admission passage and thereafter uncover the openings 115 in the cylinder adjacent the exhaust passage whereby a suction effect is produced in said cylinders to scavenge the same.

3. In a two cycle internal combustion engine, the combination with a casing having 120 a compressed air chamber therein, of a pair of cylinders within said casing, a combustion chamber common to both said cylinders, a fuel admission passage leading to 125 one of said cylinders and an exhaust passage 130

leading from the other cylinder, said cylinder adjacent the fuel passage having openings communicating with the compressed air chamber, and said cylinder adjacent the exhaust passage having openings certain of which communicate with said compressed air chamber and others of which communicate with said exhaust passage, a piston movable in each cylinder, and means for operating said pistons whereby the openings in the cylinder adjacent the admission passage are first uncovered to admit a charge of scavenging air to said cylinders and thereafter the openings in the other cylinder are uncovered to permit the passage of compressed air therethrough to the exhaust passage and the creation of a suction action in said cylinders.

4. In a two cycle internal combustion engine, the combination with a casing having a compressed air chamber therein, of a pair of cylinders within said casing, a combustion chamber common to both cylinders, a fuel admission passage leading to one of said cylinders and an exhaust passage leading from the other cylinder, said first named cylinder having openings communicating with the compressed air chamber and said second named cylinder having openings certain of which communicate with the air chamber and others of which communicate with the exhaust passage, a partition adjacent the second named cylinder for separating the openings therein which communicate with the compressed air chamber from those which communicate with the exhaust passage, a piston movable in each cylinder, and means for operating said pistons whereby the openings in the first named cylinder are uncovered before those in the second named cylinder.

5. In a two cycle internal combustion engine, the combination with a casing having a compressed air chamber therein, of a pair of cylinders within said casing the wall of each cylinder having openings through which compressed air from said chamber may flow, a combustion chamber common to both cylinders at one end thereof, a fuel admission passage communicating with one of said cylinders, an exhaust passage communicating with the other of said cylinders, a piston operable in each cylinder, means for operating said pistons whereby the openings in the cylinder communicating with the

admission passage are first uncovered to the flow of compressed air from the compressed air chamber to scavenge such chamber and thereafter the second piston is moved to uncover the openings therein and the exhaust passage whereby compressed air will flow through said last named openings to cause a suction action in both cylinders and complete the scavenging operation, and a valve for controlling the admission of fuel to said engine, said valve comprising a chamber adapted to receive fuel and supply the same to the fuel admission passage and an additional chamber within the first named valve chamber and adapted to communicate with a carburetor.

6. In a two cycle internal combustion engine, the combination with a casing having a compressed air chamber therein, of a pair of cylinders within said casing the wall of each cylinder having openings through which compressed air from said chamber may flow, a combustion chamber common to both cylinders at one end thereof, a fuel admission passage communicating with one of said cylinders, an exhaust passage communicating with the other of said cylinders, a piston operable in each cylinder, means for operating said pistons whereby the openings in the cylinder communicating with the admission passage are first uncovered to the flow of compressed air from the compressed air chamber to scavenge such chamber and thereafter the second piston is moved to uncover the openings therein and the exhaust passage whereby compressed air will flow through said last named openings to cause a suction action in both cylinders and complete the scavenging operation, and a valve for controlling the admission of fuel to said engine, said valve comprising a fuel chamber having a fuel admission port adjacent one of its ends, said fuel chamber adapted to receive fuel and supply the same to the fuel admission passage, and an additional chamber within the fuel chamber and adapted to communicate with a carburetor.

In testimony whereof I have signed this specification in presence of two subscribing witnesses.

CARL RUDQVIST.
